UNITED STATES PATENT OFFICE.

GEORGE A. SHAW, OF TORONTO, ONTARIO, CANADA.

HAND-GRENADE.

1,312,004.

Specification of Letters Patent.

Patented Aug. 5, 1919.

Application filed August 31, 1917. Serial No. 189,226.

To all whom it may concern:

Be it known that I, Lieutenant Colonel GEORGE ALEXANDER SHAW, a subject of the King of Great Britain, and resident of the 5 city of Toronto, county of York, Province of Ontario, in the Dominion of Canada, have invented certain new and useful Improvements in Hand-Grenades, as described in the following specification and illustrated 10 in the accompanying drawings, that form part of the same.

The principal objects of the invention are, to devise a form of grenade which may be thrown with great accuracy and for a 15 considerable distance and will be very deadly in its exploding effect, and further, to provide a form of grenade which will be extraordinarily safe in handling and which may be manufactured at extremely 20 low cost.

The principal features of the invention consist in the novel disk shape of the grenade and in the novel shape and arrangement 25 of disk shaped projectiles arranged within the casing, and further, in the novel construction and arrangement of parts whereby the explosive charge is ignited and whereby the igniting means is maintained in safety.

In the accompanying drawings Figure 1 30 is a perspective view of a hand grenade constructed according to my invention.

Fig. 2 is a cross sectional view taken longitudinally through the center of the holder for the igniting charge.

Fig. 3 is a cross sectional view through the line *a b* of Fig. 2.

Fig. 4 is a perspective detail of the tubular member leading to the explosive containing chamber.

Fig. 5 is a perspective detail of the tubular container member for containing the primary exploding or igniting charge.

On reference to the accompanying drawings it will be seen that my improved grenade is in the form of a double convexed disk which may be made of any suitable metal but is here shown formed of a pair of sheet metal members stamped into conical shape and secured together at the edges in a suitable seam or by electrical welding, brazing or otherwise to form a solid casing. A

circular opening 2 is arranged in the edge of the disk to receive a holder for the detonator or igniting charge.

The disk may be made of cast metal of 55 sufficient thickness for destructive purposes and in such construction it will merely be necessary to insert into the opening 2 a suitable plug carrying a fuse and detonator.

In the form herein shown a tube 3 is inserted in the opening 2 and secured to the inner end of this tube is an inner casing 4 also of convexed disk form but of considerably smaller diameter than the outer casing. This inner casing fits into the apex 65 of the inner side of the outer casing at a point opposite to the opening 2 and is adapted to contain the charge of explosive.

The tube 3 is formed with a flanged outer end 5 which abuts the edge of the outer casing and said flange is formed with a slot 6 in its periphery and a pair of notches 7 and 8 on its inner side, the notch 7 being arranged substantially in line with the edge of the disk and the notch 8 arranged about 75 90° from the notch 7.

A pair of V-shaped plates 9 of very thin flexible metal are secured at the small ends to the tube 3 adjacent to the head and extend longitudinally of said tube having 80 hardened steel pins 10 secured adjacent to the free ends and extending inwardly. The tube 3 is formed with holes 11 adapted to receive the inner ends of the pins 10.

12 is a tube closed at one end and adapted 85 to be inserted into the tube 3 having holes 13 arranged diametrically opposite and adapted to register with the holes 11 in the tube 3.

A pin 14 is secured in the outer solid end 90 of the inner tube 12 and is provided with a looped portion 15 terminating in a hook end 16. The hook end is adapted to pass through the slot 6 in the flange 5 and upon the turning of the tube said hook may be 95 moved to enter either of the notches 7 or 8. The loop 15 is so arranged in relation to the holes 13 in the inner tube that when the hook enters the notch 8 the holes 13 are out of register with the holes 11 in the rigid 100 tube 3 and when it is placed in the notch 7 the holes in the tubes are brought into

register to allow the pins 10 carried on the plates 9 to enter the inner tube.

A spring 17 encircling the tube 12 holds the hook in positive engagement with either 5 of the notches.

The tube 12 is adapted to contain a primer or igniting charge of any suitable kind which is placed therein prior to the insertion of the inner tube and when the tube is 10 inserted into the tube 3 the hook is passed through the slot 6 compressing the spring. A slight turn brings the hook into the notch 8, which is the safe position as the holes in the tubes are out of register and the position 15 is clearly indicated by the position of the loop 15. To bring the primer into firing position the tube is pressed in to release the hook from the notch 8 and it is then turned until it enters the notch 7.

20 The space between the inner and outer casings is filled with a plurality of disk shaped projectiles each formed of a convex disk shape with a sharp cutting edge. These disk shaped projectiles are inserted before 25 the two sections of the outer casing are joined together and they fit loosely within the casing and a number of them engage the thin metal plates 9 carrying the pins 10 and as these disks are preferably made of steel 30 or some other heavy metal, they will upon the jarring of the grenade with sufficient impact, spring the plates inwardly and force the pins through the holes in the tubes when they are in register and effect the ignition 35 or detonation of the priming charge. This sets off the main charge and the effect of the explosion is to split the grenade casing and scatter the sharp edged disks in every direction. The effect of this will be very 40 deadly as the disks will have an extraordinary cutting effect.

A grenade of the shape described may be 45 grasped in the hand and thrown with great accuracy and on account of its disk shape it may be thrown extraordinary distances.

The force of the impact of the disk in 50 striking the ground or other object causes the cone shaped disks to crowd against the plates 9 and the pins 10 entering the tube 55 will effect the detonation of the exploding charge.

I have shown and described herein a particular mode of exploding the charge but other means for detonating may be readily adopted by those skilled in the art without departing from the principal features herein 55 set forth, namely, the peculiar disk shape of the grenade, the shape and arrangement of the disk shaped projectiles within the 60 case and the safety feature of the rotatable tube for holding the detonator. It is within the purview of the skilled mechanic to substitute for the means for detonating the charge herein described, mechanical means

which could be released by the turning of the tube or which might be arranged to co-act with the means herein set forth.

What I claim as my invention is:—

1. A hand grenade formed of a double convexed disk-shaped shell, an explosive 70 containing receptacle arranged within said shell, means for detonating the explosive, and a plurality of projectiles arranged loosely within said shell and adapted to operate said detonating means. 75

2. A hand grenade, comprising, an outer casing, an explosive containing receptacle arranged within said outer casing, a tubular member connected with said explosive container and extending outwardly through the outer casing, a holder adapted to be inserted into said tubular member and to contain a primary explosive, a plurality of projectiles loosely arranged within the outer casing and adapted to effect the detonation of the primary explosive. 80

3. A hand grenade, comprising, an outer casing, an explosive container arranged within said casing, a tubular member connected to said explosive container and extending through the outer casing and having an opening therethrough, a detonator holder adapted to be inserted in said tubular member, means arranged upon said tubular member adapted to be projected inwardly 90 through said opening to effect the detonation of the explosive charge, and a plurality of projectiles arranged loosely within the outer casing and adapted to operate the means carried on the tubular member for 95 detonating the charge. 100

4. A hand grenade, comprising, an outer casing, an explosive container arranged within said casing, a tubular member connected to said explosive container and extending through the outer casing and having an opening through the side, a flexible member secured to the outer side of said tubular member and having a projecting member adapted to extend through the opening in the side of the tube, a holder adapted to contain a detonating charge and adapted to be inserted into said tubular member, said holder having an opening adapted to register with the opening in the tubular member 115 to allow of the passage of the projecting member carried on the flexible member, means for holding the detonating holder with the opening in register with the opening in the tube and to hold it in 120 a position to close said opening, and a plurality of projectiles loosely arranged in the outer casing adapted to force the projection on the flexible member through the openings in said tubes. 125

5. A hand grenade comprising a casing, a tubular member secured in said casing and having one end opening through the casing,

a flange arranged at the outer end of said tube having a slot therethrough and a pair of spaced notches in its inner face, a detonator tube adapted to be inserted in the former tube and having a hooked projection on its outer end adapted to pass through the slot in said flange and enter either of said notches, spring means for holding the hooked projection in engagement with either of said notches, and means released upon the 10 turning of said inner tube adapted to effect the detonation of the detonator.

5 G. A. SHAW.
